Fig. 7.

A technical drawing of a mechanical assembly. It features a central vertical rod with a slot. A horizontal plate is positioned above the slot, supported by a central pin. The plate has a central hole and two side holes. A vertical plate is attached to the side of the central vertical rod. The assembly is labeled with the following numbers: 62 at the top left, 53 at the top center, 66 at the top right, 68 at the bottom right, 67 at the bottom center, 65 at the middle left, 69 at the middle center, and 64 at the middle right.

UNITED STATES PATENT OFFICE.

WILL M. CLARK, OF EAST ORANGE, NEW JERSEY.

TALKING-MOVING-PICTURE APPARATUS.

Application filed April 5, 1922. Serial No. 549,748.

To all whom it may concern:

Be it known that I, WILL M. CLARK, a citizen of the United States, and resident of East Orange, in the county of Essex and State of New Jersey, have invented certain new and useful Improvements in Talking-Moving-Picture Apparatus, of which the following is a specification.

- This invention relates to that type of apparatus in which a phonograph or other speech reproducing mechanism, is used in connection with a moving picture machine by means of which motion pictures or pictures of objects in motion, are projected upon a screen. A talking moving picture apparatus of this class to be commercially successful must be so constructed and operated as to assure the movement of the phonograph record in synchronism with the picture film; must provide means for controlling the operation of the phonograph from the film; must provide means for instantly stopping the phonograph record without changing the relation between the record and the reproducing stylus or needle in order to prevent unnecessary and discordant sounds which occur whenever a phonograph record is slowed down before coming to a full stop; must provide means for instantly picking up the record and starting it at the right speed to immediately produce a natural and proper tone; must provide means whereby a plurality of records may be simultaneously or independently set in motion and simultaneously or independently stopped, said phonograph records being controlled by the film or by manually operable means, as may be necessary during the projection of the picture.
- It is the main object of this invention to provide a talking motion picture apparatus having all of the necessary functions and operations, as hereinbefore set forth, for completely successful commercial use. As hereinafter set forth, this invention provides means for automatically controlling the operation of the phonograph from the film. It provides means for instantly stopping phonograph records without changing the relation between the record and the reproducing stylus or needle. This permits the

entire surface of the record to be used for speech or music for the reason that the record may be stopped while the film is moving where there is no speech accompanying the pictures, and permits the speech to be instantly resumed or picked up at the proper point in the display of the film. It is manifest that this starting and stopping of the record must be so controlled that the proper tone will be maintained until the record is stopped, and the proper tone must be immediately picked up again when the record is started. It is a great advantage to secure these results without varying or changing the engaged relation of the record and the reproducing stylus or needle. By means of the invention herein described these desirable results are obtained.

This invention also provides means whereby a plurality of records may be simultaneously or independently set in motion and simultaneously or independently stopped. The means for starting and stopping the phonograph records are automatically controlled by the film as it moves through the projecting machine, and in addition said records may be controlled in starting and stopping by manually operable means so that said records may be at any time started or stopped by the operator independently of the film. This is of advantage in that it adapts the phonograph apparatus for use with non-synchronized films.

In a talking moving picture apparatus of the class herein described, the phonograph record holders are intermittently driven from the projector shaft of the moving picture machine. This shaft rotates continuously and the record holding and driving means are intermittently connected to and disconnected from said shaft, in order to start and stop the phonograph record. It is one of the important objects of this invention to provide improved means for connecting and disconnecting these mechanisms. In carrying out this part of the invention, the constantly rotating means driven by the projector shaft is heavy and is located below the table or support which carries the phonograph record holder. The phonograph record holder and the parts connected

thereto and rotating therewith are made as light as possible. The object of this is to have the inertia of the constantly moving part so much greater than the inertia of 5 the intermittently moving parts that when the load of the nonrotating parts is imposed on the rotating parts, there will be no retardation of the constantly moving parts and the nonrotating parts will be picked 10 up and almost instantly started at the normal speed of the constantly rotating parts. This is important in order that the record may start at the normal speed to produce the desired tone. The heavy constantly rotating parts are located below the table or support for the phonograph records in order that the centrifugal force thereof shall not result in undue vibrations of the phonograph records.

20 Another object of the invention is to provide friction clutch and friction brake members for starting and stopping the phonograph record holder, the said clutch and brake members being substantially co-extensive in area with the record in order that the leverage exerted on the rotating shaft by the friction members shall be co-extensive with the leverage exerted thereon by the inertia of the record and its support.

25 Another important object of the invention is to provide a novel means for connecting and disconnecting the record holder and the projector shaft. This mechanism is automatically controlled by the film and 30 is designed to operate without jar or shock.

35 There are many other important objects and advantages of the invention which will more fully hereinafter appear.

Fig. 1 is a diagrammatic view of the 40 tire apparatus and the electric circuits controlling the operation of the phonographs and the projecting machine;

Fig. 2 a diagrammatic view of the film controlling circuit making and brake devices;

50 Fig. 5 a vertical longitudinal sectional view of one half of the duplex phonograph, the other half being shown in front elevation;

Fig. 5^a an enlarged detail sectional view 55 of the lower end of the record carrying shaft and the clutch members;

Fig. 5^b a sectional view on the line 5^b—5^b of Fig. 5^a;

Fig. 6 a detail view partly in vertical section of the emergency brake operating on the projector shaft;

Fig. 7 a bottom plan view of the duplex phonograph;

60 Fig. 8 a detail vertical sectorial view 65 on the line 8—8 of Fig. 7;

Fig. 9 a detail side elevation partly in section of the step-by-step means for connecting and disconnecting the phonograph record holder and the projector shaft;

Fig. 10 a bottom plan view of the device 70 as shown in Fig. 9 with parts broken away on the line 10—10 of Fig. 9;

Fig. 11 a detail view of the means operated from the projector shaft for connecting the phonograph record holder to its rotating means, the parts being shown in the positions they occupy when the phonograph record holder is connected to its driving means;

Fig. 12 a detail view of the ratchet wheel 80 by means of which the step-by-step clutch operating means is rotated;

Fig. 13 a detail view of the toothed cam which operates to release the clutch from its locked-up or driving position;

Fig. 14 a detail view of the toothed cam which releases the toggle lever 7;

Fig. 14^a a detail view of the ratchet wheel 90 and the toothed cams for operating the clutch mechanism;

Fig. 15 a detail side elevation of a portion of the step-by-step clutch operating means showing the parts in the positions which they assume to release the clutch from its locked-up or driving position;

Fig. 16 a view similar to Fig. 11 showing the parts in the positions which they assume when the clutch means is released from its locked-up or driving position, said parts being shown in their nondriving position;

Fig. 17 a detail plan view of the clutch operating mechanism with the parts in the positions shown in Fig. 16, the clutch being in its nondriving position;

Fig. 18 a detail view similar to Fig. 15, 100 showing the ratchet wheel and toothed cams advanced one step to cause the release of the clutch mechanism from its nondriving position;

Fig. 19 a view similar to Fig. 16 showing the clutch mechanism released from its non-driving position and engaged with the projector shaft;

Fig. 20 a view similar to Fig. 17 showing the toothed cams advanced one step to cause the release of the clutch mechanism from its nondriving position, said parts being in the position corresponding to the position shown in Fig. 19;

Fig. 21 a detail horizontal sectional view 110 on the line 21—21 of Fig. 19;

Fig. 22 a side elevation of the reproducer and its supporting bracket and the feed means;

Fig. 23 a similar view showing the reproducer rotated on its supporting bracket;

Fig. 24 a bottom plan view of the reproducer as shown in Fig. 22;

Fig. 25 a detail front elevation of the reproducer as arranged in Fig. 23;

Fig. 26 a detail view of the means for automatically lifting the reproducer from the phonograph record; and

Fig. 27 a detail side elevation showing 5 the reproducer in its elevated position.

The moving picture apparatus is shown diagrammatically in Fig. 1. In that view 1 designates the reel from which the film 2 is unwound. The film passes between the usual 10 fire wheels 3, around the tension roller 4 and the feeding sprocket wheel 5, beyond which it forms the loop 6, after which it passes through the aperture plate 7, thence around the sprocket wheel 8, between the fire wheels 15 9 to the take-up wheel 10.

Behind the aperture plate 7 there are provided three sets of spring contacts 11, 12 and 13. The springs 11 are controlled by a roller 14 which is mounted on one end of a 20 pivot arm or spring and normally tends to assume a position inside of a corresponding slot in the aperture plate due to the tension of the spring 11, or of any other suitable spring. The spring 12 is controlled by a 25 roller 15 which normally tends to assume a position within a slot in the aperture plate. The spring 13 is also controlled by a roller 16 which normally tends to assume a position within a slot in the aperture plate. 30 When the film is in position, these rollers are ordinarily pressed back against their springs, as shown in Figs. 1 and 2. The projector, including the aperture plate, is illustrated diagrammatically by a rectangle 17 35 and in that rectangle the true relative positions of the rollers 14, 15 and 16 are diagrammatically illustrated. The roller 16 is shown as arranged to engage the film about midway its side edges, while the rollers 14 40 and 15 are arranged to engage the film along its longitudinal edges. The rollers 14 and 15 are adapted to pass through slots 14^a and 15^a formed in the film along its longitudinal edges while the roller 16 is held in its pressed 45 back position throughout the length of the film unless, of course, the film should break. The rollers 14 and 15 are designed to operate one or the other of the two driving means and the slots 14^a and 15^a are arranged 50 along the side of the film at the proper points to stop and start the desired records. The roller 16 is designed to operate an emergency stop whenever the film is broken.

The springs 11, 12 and 13 are contact members to which circuit wires are connected. They are adapted to engage similar contact members 11^a, 12^a and 13^a. The contacts 13 and 13^a are normally in engagement so that the circuit through them is normally 55 closed. The contacts 11 and 11^a and 12 and 12^a are normally separated so that the circuits through them are normally open. The rollers 14 and 15 hold their corresponding contacts out of engagement and release them 60 when the said rollers enter the slots provided

along the longitudinal edges of the film. The roller 16 is arranged to separate the contacts 13 and 13^a whenever a break occurs in the film. All of these circuits and the operation of the contacts will be fully herein 70 after described.

The projector shaft 18 is continuously driven by an electric motor M, said motor being connected to the shaft by a driving belt 19, so that the shaft is continuously rotated. Two phonographs A and B are arranged to be connected to and disconnected from the projector shaft. The phonograph A is controlled in its operation by an electrically controlled clutch operating means A' 75 and the phonograph B is controlled by a similar mechanism B'. The controlling means A' is energized through the roller 14 and contacts 11 and 11^a. The controlling means B' is energized through the roller 15 80 and the contacts 12 and 12^a.

In the motor circuit, interposed between the generator G and the motor, is a main switch S. The main switch is provided with a spring 20 which normally holds it in open 90 position. An electro magnetic latch 21 holds the switch closed. The magnet 22 is in a closed circuit so that said latch will be released when the circuit is broken. The circuit of this electro magnetic locking means 95 is controlled by the roller 16 and the contacts 13 and 13^a, so that should the film break, the said circuit will be immediately opened and the switch thrown to its open or circuit breaking position.

On the projector shaft is mounted a heavy fly wheel 23, said wheel also serving as a brake wheel, as shown in Fig. 6. The brake band is adapted to be clasped about the brake wheel by means of a lever and spring, 105 as will be more fully hereinafter described. It is adapted to be held in its "off" position by an electro magnet 24, said magnet being in a closed circuit controlled by the contacts 13 and 13^a and the roller 16. It is manifest, 110 therefore, that should the film break, the electro magnet 24 will be deenergized and the brake will be released for immediate engagement with the brake wheel 23. This serves as an emergency brake to immediately 115 stop the projector and the phonographs. The electro magnet 22 being in the same circuit with electro magnet 24, it will be deenergized therewith, thus simultaneously opening the main switch and applying the 120 emergency brake.

For the purpose of manually controlling the operation of the phonographs, switch devices A² and B² are provided. The switch device A² is in the circuit of the controlling device A' while the switch B² is in the circuit of the controlling device B'. By means of the two switches A² and B², the phonographs may be independently controlled 125 and may be used in connection with non- 130

synchronizing films, that is to say films that are not provided with synchronizing control slots 14^a and 15^a.

The reproducers R may be of any desired construction, but I prefer to use reproducers such as shown in Figs. 4 and 22 to 27, inclusive, and to mount said reproducers for transverse movement across the record as shown. Each reproducer is in electric circuit with a receiving instrument R' so that each reproducer may be operated independently and separately or both of said reproducers may be in operation simultaneously.

15 The combined brake and fly wheel 23 is encircled by a brake band 25, one end of which is rigidly secured to the underside of the phonograph table or support, the other end being connected to the lower end of an 20 operating lever 26, said lever being pivoted at 27 in the main frame. Connected to this lever above its pivot and near its upper end is a coil spring 28, said spring normally pulling the lever in the proper direction to 25 tightly clamp the band on the brake wheel. Said lever is provided with a handle at its upper end for manual operation. The electro magnet 24 is mounted on the table or support close to the lever 26 and said lever 30 is provided with an armature 29 adapted to be attracted by the magnet 24 when said magnet is energized. As the lever moves toward the electromagnet the brake band will be loosened on the brake wheel and the 35 pull of the magnet is opposed by the spring 28. Connected to the lever 26 and sliding through a suitable guide post is a latch bar 30, said bar being provided with a lug 31 adapted to lock against the post to hold the 40 lever close to the core of the magnet but not in actual contact therewith, so that when said latch is in operation there will be a slight air gap between the armature 29 and the core of the magnet. A spring 32 normally holds the latch bar in its upper position to prevent the lug 31 engaging and locking against the guide post. The latch 30 is provided with a finger piece 33 at its 45 free end so that when it is desired to cause the latch bar to engage the post, the said bar may be depressed against the action of the spring 32. In operation the electromagnet 24 is deenergized whenever the contacts 13 and 13^a are separated and the lever 26 is 50 then free to be thrown to its brake applying position by spring 28. The electromagnet 24 is not strong enough to pull the lever 26 to its brake releasing position, said lever therefore must be manually thrown 55 over to place the armature 29 in direct contact with the magnet core. The lever will then be held in its brake releasing position by the electromagnet against the tension of the spring 28. As soon as, however, the 60 electromagnet circuit is broken, the spring 65

will throw the lever to its brake applying position and clamp the brake band to the brake wheel. If it be desired to hold the brake band in its release position with the magnet 24 deenergized, the stop bar 30 is 70 pressed downwardly to bring the latch 31 into engagement with the guide post. When the lever is released from the magnet the spring 28 will hold the latch 30 against said post and prevent the lever 26 swinging 75 to its brake applying position. If it be desired to lock the brake in its release position and free of the electromagnet when operating the phonograph manually, it is only necessary to depress the latch bar and then 80 manually pull the lever 26 to detach the armature 29 from the electromagnet. This will permit the lever to swing away from the electromagnet slightly and as soon as the contact between the armature 29 and the 85 magnet core is broken, the spring 28 will hold the latch against the guide post. The lever and brake band will remain in this position until the lever is manually shifted 90 and will not be affected by the electromagnet.

The phonograph apparatus illustrated in the drawings is duplex in form, that is to say the phonographs A and B are mounted in a heavy table or support 35 which is carried by suitable legs. The projector shaft 18 is mounted on suitable bearings 36 secured to the under side of the table 35. The projector shaft is made sectional and the two sections are connected together at a point 100 between the phonograph driving means and the driving belt 19 by a flexible coupling 37. This coupling may be of any suitable construction and is for the purpose of preventing jars or shocks in phonograph apparatus when the phonograph record holders are connected to and disconnected from their driving means. A portion of the projector shaft may be flexible, if desired, 105 for the same purpose. 110

The phonographs A and B are exactly alike in construction and operation. For convenience of arrangement they are shown as mounted in a single table and the projector shaft is extended horizontally under the 115 table, and arranged to be connected to the driving mechanism of both of the phonographs. It is manifest, however, that the phonographs may be arranged in any desired manner and in any desired position 120 with respect to each other, so long as both of them are arranged to be driven from the projector shaft. As both of the phonographs are alike, a description of one will, of course, apply to both of them. 125

A vertically arranged hollow primary shaft 38 is arranged to extend through the table 35 and is mounted to rotate on ball bearings 39 mounted in the table. Rigidly secured to this hollow shaft below the table 130

top and below the bearings 39 is a large worm wheel 40. The projector shaft is provided with a worm 41 which engages said worm wheel so that the hollow primary shaft is directly connected to the projector shaft and is driven thereby. Rigidly secured to the lower end of the hollow shaft is a large heavy disk 42 which serves as a fly wheel and also as a clutch member. This fly wheel is horizontally disposed and is constantly rotated through its direct connection with the projector shaft. The worm 41 and the worm gear 40 are so proportioned that the disk 42 will rotate at the normal speed of a phonograph record to produce the desired tone. This speed is usually about 80 revolutions to the minute. The hollow shaft 38 is held in its bearings against vertical movement by suitable collars arranged above and below the bearings 39 and said shaft is open at both its ends. The disk 42 is as large in diameter as the largest record likely to be used on a phonograph. In actual use this disk has been made twelve inches in diameter and of heavy cast metal such as iron. It is arranged below the table 35 and on the lower end of the shaft 38 in order to place the center of gravity of the machine as low as possible to prevent undue vibrations of the machine and of the phonograph shaft because of the rotation of said heavy disk at high speed. The under side of the fly wheel disk 42 is covered with any suitable compressible friction material 43 such as felt or the like in order that said disk may act efficiently as a clutch member.

A tubular record carrying shaft 44 is mounted within the hollow primary shaft 38. The record carrying shaft 44 is free to turn within the primary shaft and is held against upward movement by a collar 45 rigidly connected to the lower end of shaft 44 and engaging the lower end of the primary shaft 38. The upper end of the record carrying shaft extends above the table 35 and above the upper end of the primary shaft. Rigidly secured to the upper end of the record carrying shaft is an upwardly extending thimble 46 to the upper end of which the record supporting table 47 is rigidly secured. The lower end of the thimble 46 abuts the upper end of the hollow shaft 38 and thus holds the shaft 44 against downward movement. Threaded into the upper end of the record carrying shaft is a double ended lag bolt 48, said bolt being provided with a central angular portion 49 to receive a suitable wrench by means of which the lower end of the lag bolt may be screwed into the upper end of the record carrying shaft. The upper end of the bolt 48 is threaded to receive a clamping nut 50, by means of which the record 51 and its holding disk 52 may be tightly clamped to the

table 47. Suitable friction material is interposed between the plate 52, the record 51 and the table 47 to hold the record firmly in position and prevent any slippage or movement thereof.

The lower end of the record carrying shaft 44 is open and mounted therein is a vertically movable clutch bar 53. The upper end of this clutch bar is formed with a key way 54 and the record carrying shaft is provided with a key 55 which engages said key way. The key way is slightly longer than the key in order to permit the clutch bar to have a slight vertical movement within the record carrying shaft. By means of the key and key way the clutch bar must rotate with the record carrying shaft, but is capable of a slight vertical or telescopic movement within said shaft. A compression spring 56 is mounted within the record carrying shaft, the lower end of said spring bearing on the upper end of the clutch bar and normally forcing it downwardly to its lowermost position. The tension of this spring may be adjusted by means of a screw 57 within the record carrying shaft and threaded through a rigid block mounted therein. The lower end of the adjusting screw is connected to the upper end of the compression spring so that by rotating said screw the tension of the spring on the clutch bar 53 may be varied. Secured to the clutch bar below the fly wheel 42 is a clutch disk 58. This clutch disk is of thin light material and is of the same diameter as the fly wheel 42. Its upper and lower surfaces are covered with compressible friction material 59 and 60, such as felt or the like. This clutch disk is preferably formed of aluminum, but it may be made of any suitable light and strong material. Below the clutch disk and supported by depending posts 61 is a stationary rigid brake disk 62. This stationary disk is equal in area to the clutch disk and to the fly wheel 42 and is covered at its upper surface with a suitable compressible friction material 63, such as felt or the like. The space between the fly wheel 42 and the stationary disk 62 is sufficient to permit the clutch disk 58 to have a slight movement up-and-down between said parts.

The stationary clutch disk is formed with an aperture at its center through which the clutch bar extends. It is manifest that the record carrying shaft must rotate with the clutch disk; and that the said clutch disk is very much lighter than the fly wheel 42. A horizontal rock shaft 64 is mounted in bearings which depend from the rigid brake disk 62. The rock shaft is radially arranged with its inner end close to the center of the clutch plate and close to the lower end of the clutch bar 53. The rock shaft 64 extends inwardly toward the center of the

table, its outer end, that is to say, the end at the greatest distance from the center of the brake member 62, is directly below the edge of said plate and is provided with a crank 5 arm 65. The inner end of said rock shaft is provided with a crank arm 66, arms 65 and 66 extending in opposite directions, as shown clearly in Fig. 7. The crank arm 66 is connected to the end of a clutch operating 10 lever 67, said lever extending directly across the vertical center or axis of the record carrying shaft, its other end being pivoted in a rigid support 68 depending from the bottom of the rigid brake disk 62. Pivoted 15 connected to the lever 67 is an upwardly extending bearing block 69 which is formed with a socket adapted to receive a free bearing ball and a rigid bearing pin secured in the lower end of the clutch bar 53 and engaging the bearing ball. The spring 56 maintains the clutch bar pressed downwardly and the bearing pin and bearing pawl in engagement with the bearing block 69. It is manifest that by rocking the shaft 20 64 in the direction indicated by the arrow in Fig. 11, the lever 67 will be swung upwardly thereby moving upwardly the clutch bar 53, compressing the spring 56 and bringing the clutch member 58 into engagement 25 with the fly wheel 42. When the rock shaft 64 is free to move in the direction indicated by the arrow in Fig. 16 the spring 56 will move the clutch bar downwardly, thereby freeing the clutch disk 58 from the fly wheel 30 and bringing it into engagement with the rigid stationary brake disk 62. The means for rocking the shaft 64 are connected to the crank arm 65.

The mechanism for rocking shaft 64 of 40 the B phonograph is designated B' and the mechanism for rocking the shaft 64 of the A phonograph is designated A'. These mechanisms are exactly alike and a description of one will serve as a description of 45 both. Each of these mechanisms is controlled by a solenoid and the circuit of that solenoid is closed and opened by film-controlled contacts, as hereinbefore described. Said circuits are also controlled by the manually operable switches A² and B² as hereinbefore set forth. Mounted on a depending bracket 70 secured to the under side of the table 35 is a solenoid 71 having a core 72 extending longitudinally therefrom and to 50 the outer end of which is pivoted a link 73. Pivoted to the outer end of said link is the upper end of a lever 74, said lever being pivoted at 75 on the bracket 70. Connected to the lever 74 is a strong 55 spring 76 which normally holds said lever against a stop 77 with the solenoid core retracted or in its outer position with respect to its coil. Pivoted to the lower end of the lever 74 below its pivot is a spring pressed 60 pawl 78 which is adapted to engage in the

teeth of a ratchet wheel 79 mounted on a rigid horizontal stud 80 carried by the bracket 70. When the solenoid is energized its core is drawn inwardly and through the connected lever and pawl the ratchet wheel is rotated the distance of one tooth. When the solenoid is de-energized the spring 76 returns the lever and its pawl to their normal inactive positions ready to again act on the ratchet wheel and rotate it another step upon the closing of the solenoid circuit. The ratchet wheel 79 is provided with sixteen 75 teeth. A spring pressed retaining pawl 81 engages the teeth of the ratchet wheel 79 and holds it against backward rotation.

Rigidly connected to the ratchet wheel 79 and rotating on the stud 80 with said ratchet wheel is a clutch releasing cam 82 and a toggle releasing cam 83. Each of these cams is provided with eight radial teeth, and said cams are so arranged with respect to each other that their teeth are staggered, a tooth of one cam lying between the adjacent teeth of the other cam. The clutch releasing cam is arranged with the operating faces of its teeth coincident with the operating faces of eight of the teeth on the ratchet wheel and the teeth of the toggle-releasing cam are arranged with their operating faces coincident with the operating faces of the other eight teeth of the operating ratchet wheel, so that the teeth of the clutch releasing cam lie in between the teeth of the toggle releasing cam when viewed in side elevation, as illustrated in Fig. 14^a. The purpose of this arrangement is that the clutch releasing cam will operate when the ratchet wheel is moved one tooth and then on the next movement of the ratchet wheel the toggle releasing cam will operate. The ratchet wheel and the two toothed cams are preferably rigidly connected together by suitable pins so that they will all rotate as a unit.

In describing the operation of the clutch releasing and the toggle-releasing cams the parts will be assumed in position with the clutch released and the phonograph not running. The parts in this position are illustrated in Figs. 15, 16 and 17. The mechanism actuated by the toothed cams is connected to the crank arm 65 of the rock shaft 64. This mechanism comprises an upwardly extending link 84 to the upper end of which is pivoted a short upwardly extending link 85, these two links constituting a toggle lever. The upper end of the link 85 is longitudinally slotted and receives a rigid pin 86 mounted in the bracket 70. The pin 86 is almost directly above the pivotal connection between the link 84 and the crank arm 65 and the joint between the toggle links is designed to be swung to one side or the other of a line drawn through the center of the pin 86 and the said pivotal connection, as will be fully hereinafter described. Piv-

- totally mounted on the bracket 70 is a toggle breaking lever 87, said lever being strongly forced toward the toggle 84-85 by a spring 88. When said lever is released, as will be hereinafter described, it moves under the impulse of the spring 88 engaging the link 84 of the toggle and forcing it toward the adjacent projector shaft 18 as shown clearly in Figs. 16 and 19. The toggle link 84 is provided with an adjustable stop 89 which is adapted to be engaged by the toggle breaking lever 87. The purpose of this is to so adjust these parts with relation to each other as to secure the proper operation thereof. Pivoted on the bracket 70, and arranged to swing horizontally, is a toggle stop 90. This stop is formed with two shoulders 91 and 91^a on opposite sides of its pivot. It is also formed between said shoulders with a horizontal setting-arm 92 which carries at its free end an inclined cam 93 which lies in the path of the link 84 of the toggle. When the clutch members are disengaged and the phonograph is not running the link 84 of the toggle will bear against the shoulder 91 of the toggle stop, being forced to that position by the toggle breaking lever 87. The toggle stop is locked against rotation on its pivot by a pawl 94 which is mounted on a vertical pivot 95 carried by the bracket 70. The pawl 94 is provided with an arm 96 on the opposite side of its pivot from the stop 90 and said arm carries at its free end a beveled head 97, the beveled edge of which lies in the path of the teeth of the toggle releasing cam 83. The teeth of the cam 83 are adapted to engage the beveled edge of the head 97 and to thrust said head outwardly away from the toothed cam, thereby swinging the pawl on its pivot and releasing it from the shoulder 91^a of the toggle stop. A spring 98 bears on the head 97 and yieldingly maintains the beveled surface of said head in the path of the teeth of the toggle releasing cam 83. When the toggle stop is released the toggle breaking lever 87 will force the link 84 of the toggle toward the adjacent projector shaft and into engagement with a fixed stop 99 (see Fig. 19). This movement of the toggle link 84 toward the projector shaft brings a dog 100, which is formed near the upper end of the link 84, into the path of a rotating expansible clutch applying cam 101 mounted on the adjacent projector shaft. This expansible cam 101 operates to force the toggle against the tension of the toggle breaking lever for the purpose of applying the clutch, as will be hereinafter described.

The cam 101 comprises a head 102 rigidly fixed to the projector shaft to turn therewith. This head is formed with an annular channel, the sides of said channel being formed by annular flanges 103. The bottom of the channel is shaped to form three flat tan-

gential surfaces 104, spaced equal distances apart around the projector shaft. The ends of these tangential surfaces are connected together by short curved surfaces, but the tangential surfaces form the major portion of the bottom of the channel and form final rigid stops for the pivoted cam arms mounted in the channel. Pivoted in the channel and on pivots passing through the two flanges 103 are three long curved cam arms 105. The pivots of said cam arms are spaced equal distances apart around the head 102 and the cam arms lie in the channel except that their beveled engaging ends project beyond the periphery of the head to form ratchet-like teeth 106. A portion of the inner side of each cam arm is formed straight in order to adapt it to lie close to the adjacent tangential surface 104. This is merely for the purpose of enabling the cam arms to be closely arranged within the flanges of the head 102. The pivot 107 of each cam arm is rigidly pinned to the cam arm and is adapted to oscillate in its flanges. Each pivot is extended beyond one of the flanges 103 and around this extended portion of the pivot is coiled a spring 108. One end of this spring is rigidly attached to a collar 109 forming a part of the head 102. The other end of the spring is attached to the pivot, and the tension of the spring holds the cam arm in the channel between the flanges 103. It is manifest that the cam arm may be thrown outward radially by pressure on the ratchet toothed portion 106, said pressure being opposite the direction of rotation of the projector shaft. The end 106 of each cam arm engages the pivoted end of the next adjacent cam arm, so that the ends of said cam arms overlie each other around the shaft when in their normal position, as shown clearly in Fig. 16.

When the toggle link 84 is released from the toggle stop and swung to the position shown in Fig. 19, the dog 100 of said link is thrown into the path of the portions 106 of the cam arms. As the projector shaft and the clutch applying cam are rotated in the direction indicated by the arrow in Fig. 19, the dog 100 will be immediately engaged by the projecting end 106 of one cam arm. The continued rotation of the projector shaft will cause the cam arm to swing outwardly on its pivot against the tension of its spring. This outward swinging movement of the cam arm will thrust the toggle link 84 toward the right hand as viewed in Figs. 16 and 19, moving the toggle link on its pivot and against the tension of the spring on the toggle breaking lever 87. As the projector shaft continues to rotate the engaged cam arm will be extended laterally toward the right, as viewed in Fig. 19, until the pivot of the engaged cam arm passes above a line drawn through

the center of the projector shaft and the end of the dog 100. When the pivot has reached this point in its movement its point of greatest extension will have been reached and the toggle link 84 will be near the limit of its movement toward the right. As the pivot rises above said point the engaged cam arm will be gradually withdrawn from under the dog until it finally snaps off the end thereof. The spring around the pivot of the engaged cam arm will then immediately swing the cam arm to its inner normal position. As the engaged cam arm is gradually extended or moved outwardly through its engagement with the dog 100, its pivoted end will swing around and force outwardly the contacting end of the next adjacent cam arm. The two cam arms will then move outwardly against the tension of their springs and when the second cam arm has been moved outwardly or extended somewhat, its pivoted end will pick up and move outwardly the third cam arm. All of these cam arms will be somewhat extended at the time when the engaged cam arm has reached its point of greatest extension. The result is that there is a constantly increasing tension placed upon the engaged cam arm, as the said cam arm forces the link 84 of the toggle across its dead center. When the extended cam arm wipes over the nose of the dog 100 it gives the final thrust to the link 84. This position of the parts is shown in Fig. 11. At this point in the rotation of the projector shaft, one edge of the engaged cam arm lies against the adjacent tangential face 104 of the cam head 102. This holds the cam arm rigid and insures the full throw of the toggle link 84. When the engaged cam arm is released from the dog 100 all of the cam arms will be immediately returned to their normal inner positions by their springs 108. The toggle links 84 and 85 are thrown over slightly beyond a line drawn through the pin 86 and the center of the pivotal connection between the lower end of the link 84 and its connected crank arm 65. The purpose of this is to hold the toggle beyond its dead center and in its clutch applying position. The movement of the toggle link 84 to the position shown in Fig. 11 rests the toggle stop, as shown in Fig. 9. As the link 84 is thrown over, as described, the toggle breaking lever 87 is moved on its pivot to bring its latch 87^a into engagement with a latch 109 which is rigidly mounted on a rocking pivot 110. The latch 109 is spring pressed, as will be presently described, and holds the toggle breaking lever in its latched position. The link 85 is slotted at its upper end to permit the link 84 to swing as described. The pin 86 serves as a thrust block and engages the lower wall of the slot in the link 85 as

the toggle is thrown to and over its dead center. As the toggle links are brought to a straight line the crank arm 65 is swung downwardly and the shaft 64 rocked in its bearings. The crank arm 66 of said rock shaft will be swung upwardly, thereby forcing upwardly the lever 67. This upward movement of the lever 67 forces the clutch bar 53 upwardly and brings the clutch plate 58 into engagement with the clutch member 42. The upward movement of the clutch bar compresses the spring 56. The tension of the spring 56 will maintain the link 85 pressed upwardly against the stop 86 and said stop will prevent the spring 56 releasing the clutch. The toggle lever in its final clutch-applying position is only slightly beyond its dead center, and there will be no appreciable relaxing of the pressure of the clutch plate 58 against the clutch member 42. The clutch members will remain in engagement until the latch 109 is released to permit the toggle breaking lever to throw the toggle across its dead center. It will, of course, be understood that when the toggle is thrown across its dead center and broken, the spring 56 will immediately throw it to the position shown in Fig. 16, and separate the clutch members. The lever 87 serves as a stop to hold the toggle in its clutch-applied position. When the toggle is thrown across its dead center an additional compression of the friction facings 43 and 59 is caused, and these facings tend to expand after the toggle has passed its dead center and thus assist the spring 56 in holding the toggle against the lever 87. The rocking pivot 110 is mounted in the bracket 70 and on said pivot is rigidly secured a crank arm 111. A spring surrounds the pivot with one end bearing on the crank arm 111 and one end bearing against a rigid stop. Said springs force the cam arm upwardly and also force the latch 109 upwardly into its latching position. The end of the crank arm 111 is in the path of the clutch releasing cam 82 and is adapted to be engaged by said teeth as said cam is rotated through the ratchet wheel 79. As hereinbefore stated, the teeth of the clutch releasing cam alternate with the teeth of the toggle releasing cam 83. After the solenoid has moved the ratchet wheel one tooth and has operated the toggle releasing cam, the next impulse from the solenoid will bring a tooth of the clutch releasing cam into engagement with the crank arm 111 and depress said arm sufficiently to release the latch 109 from the toggle breaking lever 87. The teeth of the clutch releasing cam are so arranged that they will hold the latch 109 in its release position, as shown clearly in Figs. 15 and 16, and the said latch and the crank arm 111 will not be released until the solenoid has given the ratchet wheel its

next impulse, so that the clutch braking lever will have ample time to swing out of the path of the latch 109 before said latch is released from the cam 82. This insures 5 the operation of the toggle breaking lever. The crank arm 111 is stopped in its upper position by a stop pin 113.

The release and operation of the toggle breaking lever permits the spring 56 to move 10 downwardly the clutch bar 53 and the clutch member 58, said clutch bar sliding in the record-carrying shaft 44. The downward movement of the clutch bar will carry the clutch member 58 into engagement with the 15 stationary brake member 62 and the record will be instantly stopped without varying the relation of the record and the reproducing stylus. As hereinbefore described, the clutch member 58 and the entire record holding mechanism is made as light as possible 20 in order to reduce the inertia of these moving parts to a minimum. This insures an instant stoppage of the record holder and the clutch member 58.

25 It is manifest that the yieldable expandable cam 101 will operate without jar or shock and yet will act so quickly that the engagement between the clutch member 58 and the constantly rotating fly wheel and 30 clutch member 42 will be almost instant and the clutch 58 and the record holder will immediately be started at the normal speed to produce the desired tone. As hereinbefore pointed out, the inertia of the non-rotating part will be so much less than the 35 inertia of the moving fly-wheel clutch member 42 that the member 42 will not be retarded by the imposition of the extra load. This operation is further assisted by the 40 fact that the projector shaft carries a constantly rotating heavy fly wheel 23 and also that the driving gears are heavy and add considerably to the inertia of the constantly moving mechanism. The spring 56 is of 45 sufficient strength to force the clutch member 58 into engagement with the stationary brake member 62 with the necessary force to stop the record carrying mechanism instantly.

50 When the film breaks and the apparatus is stopped by opening the main motor circuit and applying the emergency brake, it is necessary to re-thread the film through the projecting machine. When this is done, it is necessary to advance the phonograph record in order to synchronize it with the film. This is done by rotating the clutch member 58 sufficiently to bring the phonograph record in synchronism with the film. 55 To facilitate this operation, the brake plate is provided at its edge with an upstanding index 114 which is adapted to register with index marks 115 on the clutch member 58. These index marks indicate the distance 60 which the clutch member 58 must be ro-

tated to compensate for a given number of pictures passed through the machine in the act of re-threading the film. By noting the number of pictures passed through the machine the exact distance which the record 70 must be moved to compensate for those pictures may be readily determined. In practice it has been found desirable to advance the film a distance corresponding to the length of 36 pictures for re-threading 75 it through the projecting machine after a break. For convenience and to avoid the necessity of counting the pictures, a standard gage indicating the required length may be used in measuring off the film. In order 80 that the synchronization may be resumed it is necessary to advance the record to correspond to the advancement of the film, as usually arranged three revolutions of the record disk is sufficient. When the film 85 breaks the contacts 11-11^a and 12-12^a will re-engage each other, and the clutch of the operating phonograph will be thrown out and the record instantly stopped. Mounted 90 in suitable bearings and supports 116 95 extending upwardly from the table 35 is a threaded shaft 117. This shaft extends horizontally over the phonograph record and is driven by a belt 118 which passes over a pulley 119 on the threaded shaft and a pulley 120 secured to the record driving shaft 46. Mounted on the threaded shaft is a split clamp 121 consisting of two semi-cylindrical members 122 and 123 hinged together along their lower edges at 124. This 100 split clamp is lined with a heavy pad of felt 125 which is adapted to be brought into engagement with the threaded shaft 117 to serve as a nut or threaded member 105 for moving the split clamp along the threaded shaft. The felt pad 125 absorbs any little shocks or vibrations incident to the travel of the clamp 121 along the shaft 117 and prevents their being transmitted to the 110 reproducer. Around the pivot 124 is arranged a spring 126 whose ends engage the two members of the clamp and hold them in clamping engagement with the screw shaft. The member 123 is provided with a horizontally extending arm 127 to which is 115 pivoted an arm 128, a duplex reproducer 129 being rotatably mounted on said arm. The reproducer carries the usual reproducing stylus 130, and said reproducer is supported in position over the phonograph record. The rotation of the phonograph record causes the rotation of the screw shaft and the consequent feeding of the reproducer along said shaft in order to enable it 120 to follow the groove in the record. A duplex reproducer with a set of reproducing elements and electrical connections on either side is provided in order that either set may be used in case the other should be disabled. The reproducer is swiveled upon 125 130

the arm 128 and is adapted to be turned through an angle of ninety degrees as shown in Figs. 22 and 23 to accommodate it to records having either laterally or vertically cut grooves.

The member 123 of the split clamp is provided with an upwardly extending pin 131. The inner bearing 116 carries an upwardly extending rigid cam 132. When the split 10 clamp approaches the inner end of the shaft 117, the pin 131 will engage the cam 132 and will rotate the split clamp on the threaded shaft and lift the reproducer from the record. The cam 132 is formed with a stop 15 shoulder 133 against which the pin 131 will come to rest after the reproducer has been lifted from the phonograph record. This shoulder also stops the longitudinal movement of the split clamp on the threaded 20 shaft. The felt lining within the clamp permits the threaded shaft to rotate after the pin is in engagement with the stop 133, should the phonograph record carrying mechanism continue to rotate after the reproducer has been lifted therefrom.

The member 123 of the split clamp is provided with an upwardly extending finger piece 134; and the member 122 is formed with a corresponding finger piece 135 which 30 is pivoted thereto near its upper edge. The finger piece 135 is provided with a bearing member 136 which impinges against the finger piece 134 near its lower edge. By forcing together the upper ends of the finger piece 35 the lower end of the finger piece 134 will rock outwardly and thereby separate the two members of the clamp. This permits the clamp to be opened, so that the reproducer may be adjusted longitudinally along 40 the shaft 117. When it is desired to detach the reproducer from the shaft the member 122 is moved bodily downwardly against the spring 126 as indicated in dotted lines in Fig. 23.

45 The provision of clutch surfaces of large area renders practicable the use of a soft, compressible material, such as felt, for facing said surfaces. The use of smaller clutch surfaces would result in a greater pressure 50 per unit of area upon the soft compressible facings and cause them to wear away or lose their compressibility. By the use of clutch surfaces of large area faced with a soft compressible material, a positive, velvety pick-up 55 of the clutches is obtained, with but a small pressure upon the clutch facings. The location of the clutch members at a considerable distance below the record and on the 60 opposite side of the shaft bearings therefrom also helps to protect the record from shock when the clutch is operated.

What I claim is:

1. The combination of a switch-operating 65 moving picture film, a plurality of switches controlled by said film, a circuit individual

to each switch, a phonograph individual to each circuit and controlled thereby, means controlled by the said switches for individually starting and stopping the phonographs, a reproducer operating on each phonograph, a circuit for each reproducer, a receiver electrically connected to each reproducer and independently operated thereby, means for moving the film, means for driving the phonograph from the film moving means, and a film-controlled switch for stopping the film-moving means.

2. A talking moving picture apparatus comprising means for moving a picture film, a shaft for supporting and driving a phonograph record, a fly-wheel driving-plate of large diameter and of greater inertia than the said record and its shaft, means for constantly rotating said plate from the film moving means, a light clutch plate connected to the record-carrying shaft and substantially equal in diameter to the driving plate, a stationary brake disk adjacent the clutch plate and substantially equal thereto in diameter, a film-controlled switch, and an electro-magnetic step-by-step mechanism controlled by said switch for moving the clutch plate alternately into engagement with the driving plate and the brake disk.

3. A talking moving picture apparatus comprising means for moving a picture film, a shaft for supporting and driving a phonograph record, a driving plate, means for rotating said plate from the film moving means, a clutch plate rotatable with the record-carrying shaft but movable axially thereof, a stationary brake disk adjacent the clutch plate and on the opposite side thereof from the driving plate, a film-controlled switch, and an electro-magnetic step-by-step mechanism controlled by said switch for moving the clutch plate alternately into engagement with the driving plate and the brake-disk.

4. A talking moving picture apparatus comprising means for moving a picture film, a frame, a vertical hollow drive shaft mounted therein, a record-carrying shaft extending through the drive shaft, a fly-wheel driving plate on the lower end of the drive shaft below the frame top, a record support on the upper end of the record-carrying shaft above the frame top, means for rotating the drive shaft from the film moving means and connected to the said shaft below the frame top, a clutch plate below the driving plate and connected to rotate with the record shaft and movable to and from the driving plate, a stationary brake-disk below the clutch plate, a film-controlled switch, and an electro-magnetic step-by-step mechanism controlled by said switch for moving the clutch plate alternately into engagement with the driving plate and the brake-disk.

said plate, a stationary brake disk below the clutch plate, yieldable means for normally thrusting the clutch plate into engagement with the brake disk, and film-controlled means for governing the movement of the clutch plate to the driving plate and to the brake disk.

11. A talking moving picture apparatus comprising means for moving a picture film, a shaft for supporting and rotating a phonograph record, a drive shaft, a heavy fly-wheel driving plate of large diameter and of greater weight than the record-carrying shaft and its connected rotating elements whereby the weight of the record-carrying shaft and its connected elements when not rotating may be imposed upon the rotating driving plate without retarding the speed of the driving plate, means for constantly rotating the drive shaft and driving plate from the film moving means, a light-weight clutch plate connected to the record-carrying shaft and adapted to move axially thereof, said clutch plate being substantially equal in diameter to the driving plate, a stationary brake disk adjacent the clutch plate and substantially equal thereto in diameter, a film-controlled switch, and an electro-magnetic means operated by said switch to govern the movements of the clutch plate to the driving plate and to the brake disk.

12. A talking moving picture apparatus comprising means for moving a picture film, a hollow primary drive shaft, a record-carrying shaft extending through the drive shaft, a driving plate connected to the lower end of the drive shaft, a clutch plate connected to the lower end of the record-carrying shaft and movable axially thereof, a stationary brake disk below the clutch plate, a spring normally thrusting the clutch plate into engagement with the brake disk, a film-controlled switch, a step-by-step electro-magnetic means controlled by said switch, a rotatable expandible cam operatively connected to the film moving means, means adapted to be engaged by the expandible cam for thrusting the clutch plate into engagement with the driving plate, means for locking the clutch plate thrusting means out of the path of the expandible cam, and means controlled by the electro-magnetic device for releasing said locking means to permit the said thrusting means to move into the path of said cam.

13. A talking moving picture apparatus comprising means for moving a picture film, a drive shaft, a record-carrying shaft, a driving plate connected to the drive shaft, a clutch plate connected to the record-carrying shaft and movable axially thereof, a stationary brake disk adjacent the clutch plate, means normally thrusting the clutch plate into engagement with the brake disk,

a film-controlled switch, a step-by-step electro-magnetic means controlled by said switch, a rotatable expandible cam, means adapted to be engaged by the expandible cam for thrusting the clutch plate into engagement with the driving plate, means for locking the clutch plate thrusting means out of the path of the expandible cam, and means controlled by the electro-magnetic device for releasing said locking means to permit the said thrusting means to move into the path of said cam.

14. A talking moving picture apparatus comprising means for moving a picture film, a drive shaft, a record-carrying shaft, a driving plate connected to the drive shaft, a clutch plate connected to the record-carrying shaft and movable axially thereof, a stationary brake disk adjacent the clutch plate, means normally thrusting the clutch plate into engagement with the brake disk, a film-controlled switch, a step-by-step electro-magnetic means controlled by said switch, a rotatable expandible cam, means adapted to be engaged by the expandible cam for thrusting the clutch plate into engagement with the driving plate, means for locking the clutch plate thrusting means out of the path of the expandible cam, means controlled by the electro-magnetic device for releasing said locking means to permit the said thrusting means to move into the path of said cam, means for locking the clutch plate thrusting means in position to hold the clutch plate locked to the driving plate, and means controlled by the electro-magnetic device for releasing said locking means to permit the clutch plate to move into engagement with the brake disk.

15. A talking moving picture apparatus comprising means for moving a picture film, a shaft for supporting and rotating a phonograph record, a drive shaft, a heavy fly-wheel driving plate of large diameter and of greater weight than the record-carrying shaft and its connected rotating elements whereby the weight of the record-carrying shaft and its connected elements when not rotating may be imposed upon the rotating driving plate without retarding the speed of the driving plate, means for constantly rotating the drive shaft and driving plate from the film moving means, a light-weight clutch plate connected to the record-carrying shaft, said clutch plate being substantially equal in diameter to the driving plate, a stationary brake disk adjacent the clutch plate and substantially equal thereto in diameter, a film-controlled switch, and an electro-magnetic means operated by said switch to govern the movements of the clutch plate to the driving plate and to the brake disk.

16. A talking moving picture apparatus comprising means for moving a picture film, a drive shaft, a record-carrying shaft,

- a driving plate connected to the drive shaft, a clutch plate connected to the record-carrying shaft and movable axially thereof, a stationary brake disk adjacent the clutch plate, means normally thrusting the clutch plate into engagement with the brake disk, a film-controlled switch, a step-by-step electro-magnetic means controlled by said switch, a toothed clutch-releasing cam, a toothed toggle-releasing cam in fixed relation to the clutch-releasing cam, both of said cams being rotated step by step by the electro-magnetic means, a rotatable expansible cam, means adapted to be engaged by the expansible cam for thrusting the clutch plate into engagement with the driving plate, means for locking the said thrusting means out of the path of the expansible cam, means operated by the toggle-releasing cam for releasing said locking means to permit the thrusting means to move into the path of said cam, means for locking the clutch plate thrusting means in position to hold the clutch plate locked to the driving plate, and means operated by the clutch-releasing cam for releasing said locking means to permit the clutch plate to move into engagement with the brake disk.
17. A talking moving picture apparatus comprising means for moving a picture film, a drive shaft, a record-carrying shaft, a driving plate connected to the drive shaft, a clutch plate connected to the record-carrying shaft and movable axially thereof, a stationary brake disk adjacent the clutch plate, means normally thrusting the clutch plate into engagement with the brake disk, a film-controlled switch, a step-by-step electro-magnetic means controlled by said switch, a toothed clutch-releasing cam, a toothed toggle-releasing cam in fixed relation to the clutch-releasing cam, both of said cams being rotated step by step by the electro-magnetic means, a rotatable expansible cam, means adapted to be engaged by the expansible cam for thrusting the clutch plate into engagement with the driving plate, means for locking the said thrusting means out of the path of the expansible cam, means operated by the toggle-releasing cam for releasing said locking means to permit the thrusting means to move into the path of said cam, means for locking the clutch plate thrusting means in position to hold the clutch plate locked to the driving plate, and means operated by the clutch-releasing cam for releasing said locking means to permit the clutch plate to move into engagement with the brake disk.
18. A talking moving picture apparatus comprising means for moving a picture film, a drive shaft, a record-carrying shaft, a driving plate connected to the drive shaft, a clutch plate connected to the record-carrying shaft and movable axially thereof, a stationary brake disk adjacent the clutch plate, means normally thrusting the clutch plate into engagement with the brake disk, a film-controlled switch, a step-by-step electro-magnetic means controlled by said switch, a rotatable expansible cam, a toggle lever, means connecting the toggle lever to the clutch plate, means for locking the toggle lever out of the path of the expansible cam, means controlled by the electro-magnetic device for releasing the toggle lever to permit it to move into the path of said cam, means for locking the toggle lever in position to hold the clutch plate in engagement with the driving plate, and means operated by the electro-magnetic device for releasing said locking means to permit the clutch plate to be moved into engagement with the brake disk.
19. A talking moving picture apparatus comprising means for moving a picture film, a drive shaft, a record-carrying shaft, a driving plate connected to the drive shaft, a clutch plate connected to the record-carrying shaft and movable axially thereof, a stationary brake disk adjacent the clutch plate, means normally thrusting the clutch plate into engagement with the brake disk, a film-controlled switch, a step-by-step electro-magnetic means controlled by said switch, a toothed clutch-releasing cam, a toothed toggle-releasing cam in fixed relation to the clutch-releasing cam, both of said cams being rotated step by step by the electro-magnetic means, a rotatable expansible cam, a toggle lever, means connecting the toggle lever to the clutch plate, means for locking the toggle lever out of the path of the expansible cam, means controlled by the toggle-releasing cam for releasing the toggle lever to permit it to move into the path of said cam, means for locking the toggle lever in position to hold the clutch plate in engagement with the driving plate, and means operated by the clutch-releasing cam for releasing said locking means to permit the clutch plate to be moved into engagement with the brake disk.
20. A talking moving picture apparatus comprising means for moving a picture film, a drive shaft, a record-carrying shaft, a driving plate connected to the drive shaft, a clutch plate connected to the record-carrying shaft and movable axially thereof, a stationary brake disk adjacent the clutch plate, means normally thrusting the clutch plate into engagement with the brake disk, a film-controlled switch, a step-by-step electro-magnetic means controlled by said switch, a toothed clutch-releasing cam, a toothed tog-

gle-releasing cam in fixed relation to the clutch-releasing cam, both of said cams being rotated step by step by the electro-magnetic means, a rotatable expansible cam, a toggle lever, means connecting the toggle lever to the clutch plate, means for locking the toggle lever out of the path of the expansible cam, means controlled by the toggle-releasing cam for releasing the toggle lever to permit it to move into the path of said cam, means for locking the toggle lever in position to hold the clutch plate in engagement with the driving plate, and means operated by the clutch-releasing cam for releasing said locking means to permit the clutch plate to be moved into engagement with the brake disk, the teeth of the clutch-releasing cam being staggered with respect to the teeth of the toggle-releasing cam whereby said cams will operate their associated devices on alternate steps of the electro-magnetic device.

21. A talking moving picture apparatus comprising means for moving a picture film, a drive shaft, a record-carrying shaft, a driving plate connected to the drive shaft, a clutch plate connected to the record-carrying shaft and movable axially thereof, a stationary brake disk adjacent the clutch plate, means normally thrusting the clutch plate into engagement with the brake disk, a film-controlled switch, a step-by-step electro-magnetic means controlled by said switch, a rotatable expansible cam provided with a plurality of radially swinging yieldable cam arms, means adapted to be engaged by the arms of the expansible cam for thrusting the clutch plate into engagement with the driving plate, means for locking the clutch plate thrusting means out of the path of the arms of the expansible cam, and means controlled by the electro-magnetic device for releasing said locking means to permit the said thrusting means to move into the path of the arms of said cam.

22. A talking moving picture apparatus comprising means for moving a picture film, a drive shaft, a record-carrying shaft, a driving plate connected to the drive shaft, a clutch plate connected to the record-carrying shaft and movable axially thereof, a stationary brake disk adjacent the clutch plate, means normally thrusting the clutch plate into engagement with the brake disk,

a film-controlled switch, a solenoid, a ratchet wheel adapted to be rotated by said solenoid step by step, a toothed clutch-releasing cam and a toothed toggle-releasing cam connected to said ratchet wheel, the teeth of said cams being staggered with respect to each other to operate on alternate steps of the ratchet wheel, and means operated by said toothed cams for controlling the movement of the clutch plate to the driving plate and to the brake disk.

23. A talking moving picture apparatus comprising means for moving a picture film, a vertical hollow drive shaft, means for supporting said shaft, means for constantly driving said shaft from the film moving means, a heavy fly-wheel driving plate rigidly connected to the lower end of the drive shaft, a record-carrying shaft extending through the drive shaft, a record support mounted on said shaft above the drive shaft, a clutch bar slidable in the record-carrying shaft and connected to turn therewith, a light-weight clutch plate connected to said clutch bar below the driving plate, a stationary brake disk below the clutch plate, a spring within the record-carrying shaft and normally thrusting the clutch plate into engagement with the brake disk, and film-controlled means for moving the clutch plate into engagement with the driving plate and for releasing it from said driving plate.

24. A talking moving picture apparatus comprising a projector shaft, a motor, means connecting said motor to the projector shaft, a phonograph record supporting shaft, means connecting said shaft to the projector shaft, a brake disk on the projector shaft, a brake band for said disk, a pivoted lever connected to said band and carrying an armature, an electro-magnet adapted to move said lever to release the brake band from the brake disk, a film-controlled normally closed switch in the circuit of the electro-magnet, a spring connected to said lever and normally applying the brake band to the brake disk, and means for locking the lever to hold the brake band released when the electro-magnet is de-energized.

In testimony whereof I hereunto affix my signature.

WILL M. CLARK.
